(57) **CLAIM**

We claim the ornamental design for a combined squeegee and support frame, as shown and described.

DESCRIPTION

FIG. 1 is a bottom perspective view of a squeegee assembly embodying aspects of the invention.

FIG. 2 is a top perspective view of the squeegee assembly shown in FIG. 1.

FIG. 3 is a top view of the squeegee assembly shown in FIG. 1.

FIG. 4 is a front view of a squeegee assembly shown in FIG. 1.

FIG. 5 is a bottom view of the squeegee assembly shown in FIG. 1.

FIG. 6 is a rear view of the squeegee assembly shown in FIG. 1.

FIG. 7 is a right side view of the squeegee assembly shown in FIG. 1.

FIG. 8 is a left side view of the squeegee assembly shown in FIG. 4.

FIG. 15 is a top perspective view of a squeegee support frame embodying aspects of the invention.

FIG. 16 is a bottom perspective view of the squeegee support frame shown in FIG. 15.

FIG. 17 is a front view of the squeegee support frame shown in FIG. 15.

FIG. 18 is a bottom view of the squeegee support frame shown in FIG. 15.

FIG. 19 is a rear view of the squeegee support frame shown in FIG. 15.

FIG. 20 is a right side view of the squeegee support frame shown in FIG. 15; and,

FIG. 21 is a left side view of the squeegee support frame shown in FIG. 15.

The broken lines shown in the drawings depict unclaimed portions of the article and form no part of the claimed design.
